SEALING RING FOR CENTRIFUGAL DEVICES

Russel D. Acton, Chicago, Ill.

Application April 23, 1947, Serial No. 743,344

6 Claims. (Cl. 137—140)

1

This invention relates to centrifugal devices. More specifically it relates to a sealing ring for an annular orifice of a cream separator bowl.

In the use of centrifugal devices, particularly those used for separating cream from milk, it has been found desirable to use a large number of closely spaced skimming disks. Due to the accumulation of fats and other materials in the milk during separation, it is necessary to periodically wash the elements of the separating bowl. By merely putting washing liquid through the separating mechanism, there is no sufficient velocity within the bowl to carry the accumulated materials away. It has been found, however, that by providing outlets at the periphery of the bowl, and by using sealing means to close these outlets which can be released during washing operations, sufficient washing liquid can be put through the bowl at sufficient velocities to clean the accumulated materials therefrom. By such a washing operation it is not necessary to disassemble the bowl structure after each use.

An important object of the present invention is to provide an improved sealing ring for centrifugal devices having a substantial annular outlet around the periphery thereof.

A more specific object is to provide a sealing ring including distendable or elastic material which stretches or distends under the influence of centrifugal force to engage inner surfaces of a bowl structure adjacent a substantial annular orifice to provide a sealing means at predetermined speeds of rotation.

Another important object is to provide a supporting structure for the elastic sealing means which stabilizes said ring against undesirable shifting movement in an axial direction with respect to the rotation of the device and against eccentric movement with respect to the axis of rotation.

Another specific object is to provide control means, either as a rigid structure or as a plurality of resilient means, to modify the stretching or distending movement of the elastic sealing ring.

The above objects and others, which will be apparent from the description to follow, may be accomplished by various structures, several modifications of which are shown in the drawings in which:

Figure 1 is an elevation of a conventional frame separator bowl structure with the tinware broken away in section and with a portion of the bowl structure broken away in section to better illustrate the invention;

Figure 2 is an enlarged view of the broken away bowl section shown in Figure 1;

Figure 3 is a reduced scale section taken substantially on the line 3—3 of Figure 1;

2

Figure 4 is a section similar to Figure 2 showing a modified sealing ring structure;

Figure 5 is a partial plan view of the peripheral portion of the structure shown in Figure 4;

Figure 6 is a section similar to Figure 2 showing a modification of the sealing ring structure;

Figure 7 is a peripheral edge view of the structure shown in Figure 6;

Figure 8 is a section similar to Figure 2 showing a modification of the sealing ring structure;

Figure 9 is an elevation of a section of the sealing ring structure of Figure 8;

Figure 10 is a section shown in another modification similar to the structure shown in Figure 8; and

Figure 11 is a view substantially on the line 11—11 of Figure 10.

As cream separator bowl structures of the conical disk type are very conventional and well known in the art, and as the invention relates only to a releasable seal for a peripheral annular opening in a centrifugal bowl structure, only such portions of a centrifugal cream separator have been shown as are necessary to provide an illustrative background for the invention. In Figure 1 a bowl structure designated in its entirety by the reference character 10 is shown surrounded by the usual tinware including a cover 11, a milk spout 12 and a cream spout 13. The milk spout 12 is carried on a cylindrical wall 14 which is secured to a bottom wall 15 to provide a milk receiving chamber 16. The cylindrical wall 14 is provided with a bead 17 and a depending cylindrical flange 18 which fits within a cylindrical wall 19 to which the cream spout 13 is secured. A milk feed tube 20 is illustrated for delivering milk to the bowl.

As is conventional practice, the bowl 10 is formed of two casing members, the upper casing member 20 being conical in shape and diverging outwardly in a downward direction. The lower casing member 21 has an inner conical wall portion 22 diverging and sloping inwardly in an upward direction substantially parallel to the wall 14 of the upper casing member 20. A plurality of closely spaced separating disks 23 are mounted between the upper casing member 20 and the conical wall portion 22 of the lower casing member 21. Said disks are held in center position by a plurality of wings or webs 24, one of which is shown in Figure 1. Said wings are secured to the upper casing member 20.

The lower casing member 20 has a second conical wall portion 25 sloping outwardly in an upward direction. An annular clamping member 26 is provided with a flange 27 which overlaps a peripheral flange 28 on the upper casing member 20. Said clamping member 26 is threaded internally at its lower portion to engage threads 60 formed on the outer periphery of the wall por-

tion 25 of the lower casing member 21. A plurality of slots 29 are formed around the periphery of the clamping member 26, said slots extending entirely through said member. The slots form a substantially continuous annular opening, only such bridging portions remaining as are necessary to provide sufficient strength for clamping the two casing members 20 and 21 together and to withstand the centrifugal force developed during operation.

It will be noted that the parts described up to this point are the same in all the modifications and bear the same reference characters.

In Figures 1 and 2 a sealing ring structure is illustrated in which a flat annular sheet metal ring 30 is provided with a plurality of circumferentially spaced spacing disks or buttons 31. Said buttons are adapted to engage the adjacent edges, or opposed faces 20' and 21' respectively of the casing members 20 and 21 and space said faces apart to provide in this instance a pair of narrow annular openings 29', said openings or outlets in turn connect with the substantially continuous annular discharge opening formed by the slots 29 in the clamping ring 26.

A resilient circular sealing member in the form of a rubber ring 32 circular in cross-section is provided with a slot or recess 33 in its outer periphery adapted to fit over the inner edge of the annular member 30, whereby said sealing ring is held stabilized in position concentric with respect to the axis of rotation of the bowl structure and is also stabilized against any substantial movement in an axial direction with respect to the axis of rotation. As illustrated, the sealing ring 32 is further provided with a metal insert in the form of a metallic closed ring 34. Said ring may be free within the resilient material of the sealing ring, whereby said resilient material may be replaced or the ring may be cemented or vulcanized within the resilient material. Likewise the ring 34 may be secured to or integrally with the annular member 30 or may be free from said member.

It will be noted that the webs 24 which center the separating disks are provided with slots 35 which closely fit the outer periphery of the ring 32 when said ring is in its non-sealing position. This support acts to stabilize and hold the ring against axial movement and in a concentric position with respect to the axis of rotation. As illustrated by dotted lines in Figure 2, when the centrifugal bowl reaches a predetermined speed of rotation, the resilient material stretches due to centrifugal force thereof and moves radially outwardly into sealing position. A portion of the resistance to sealing is in a circumferential direction, a certain force being required to enlarge the circumference of the ring. A major portion of the resistance, however, to sealing is the stretch required to move each individual sector of the ring in a radial direction. This method of control makes it possible to construct a ring which can be accurately controlled to seat at a predetermined speed of rotation of the bowl structure and to likewise release at a predetermined speed when it is desired to empty the contents of the bowl and to discharge washing liquid from the bowl through the annular outlets.

In the modification shown in Figure 4, the opposed faces 20' and 21' of the casing members are spaced apart by a corrugated annular sheet metal structure 36. As said member engages the upper casing member only at the contact points 37 of

the upper corrugations and engages the lower casing member 21 only at the contact points 38 of the corrugations, a substantially free and unobstructed annular opening is provided for the escape of liquid from the bowl structure when the seal is released.

The structure 36 within the bowl is provided with a substantially flat annular portin 37' from which a plurality of oppositely directed spring fingers 38' extend. Said spring fingers are embodied in a sealing ring structure 39 which is shaped to correspond to the inside sloping surfaces of the casing members 20 and 21. The notches 34 of the webs 24 engage the inner surface of the sealing ring structure 39 when said ring is in inoperative position as illustrated. The resiliency of the material in the ring structure 39 and the resiliency of the spring fingers 38 are so proportioned that upon a predetermined speed said ring structure moves into the dotted line position, whereby portions of the bowl structure on opposite sides of the outlet between the members 20 and 21 are engaged to provide a positive seal. Likewise at a predetermined speed the sealing ring structure 39 releases to provide for the escape of liquid from the bowl structure. In this modification positive means are provided for holding the sealing ring structure against movement in an axial and radial direction and also for holding it in concentric relation, while at the same time providing in a controlled manner for seating of portions of the ring structures to provide a seal. In this modification the resistance to stretch of the resilient material in a circumferential direction is augmented by the stretching of the material in a radial outward direction and is also controlled by the resiliency of the spring fingers 38'. The resiliency of the metal material will change very little with aging and in this respect provides a more dependable seal than a sealing structure in which the resiliency of the elastic material is alone relied upon.

In the modification of Figure 6 a metal supporting ring 40 carries a plurality of radially and outwardly extending pins 41 which are clamped between the opposed faces of the upper casing member 20 and the lower casing member 21 to provide a substantially annular outlet opening. A ring 42 of resilient material has a peripheral recess 43 which sits on the inner surface of the ring 40 and may be cemented or vulcanized to said ring if desired. The inner surface of the ring 42 fits in recesses 34 of the webs 24 to further hold the ring against displacement when it is in non-sealing position as illustrated. The ring 42 is of such material that at a predetermined speed sufficient stretch is obtained in a circumferential direction and in radial outward directions at each side of the ring 40 to engage portions of the upper casing member 20 and the lower casing member 21 to provide an effective and positive seal to prevent the escape of liquid from the bowl structure at speeds above this predetermined speed. Likewise the resiliency of the material is such that the ring will contract and provide for the escape of liquid from the bowl structure at speeds below the predetermined sealing speed.

In the modifications shown in Figures 6 and 7 a simple supporting structure is provided by means of which the sealing ring is maintained in concentric position thereby adding to the stability of the bowl. It is also possible to accurately determine the speed at which such a ring will seat

and to assure substantial instantaneous sealing and insulating of all portions of the ring.

Figures 8, 9, 10 and 11 show two modifications in which the ring structure consists entirely of resilient material. In Figures 8 and 9 a resilient ring 44 circular in cross-section is provided with a plurality of oppositely directed lugs or projections 45 which are sloped and shaped to fit the sloping inside walls of the casing members 20 and 21. The opposed faces 20' and 21' of the casing members 20 and 21 are spaced apart by a plurality of headed pins 46c. In the non-sealing position illustrated in Figure 8 the lugs 45 act in addition to the inherent resiliency of the ring 44 to bridge across the outlet opening between the two casing members, thereby stabilizing the ring in an axial direction. When at the predetermined speed for which the spring 44 is designed to seat, it is necessary first to overcome the circumferential resistance to stretching of the ring and second to overcome the bridging provided by the lugs 45 which are closely spaced along the ring 44. When such a force is brought about by rotation, the ring moves outwardly with all portions seating at substantially the same time and with the ring maintaining its concentric position within very close limits. It will be noted that between the lugs 45 there is a portion 46 which is uninterrupted whereby good sealing surfaces are provided for contacting the terminating edges of the inner faces of the casing members 20 and 21.

The modification of Figures 10 and 11, while somewhat similar to that shown in Figure 8, shows supporting lugs 47 formed on the casing member 20 and lugs 48 formed on the casing member 21. Said lugs are spaced apart to engage a sealing ring 49 and along with the notches 35 in the webs 24 hold the ring 44 securely against displacement until a centrifugal force is brought about sufficiently to push each section of the rubber ring radially outwardly between the bridge lugs 47 and 48. It will be noted that the upper casing member 20 is formed with a sealing surface 59 adjacent the termination of the inner surface of the wall and that the lower casing member 21 is provided with a smooth sealing surface 51 adjacent the termination of its inner sloping surface. These sealing surfaces 50 and 51 are provided to abut the surface of the sealing ring 49 to provide a satisfactory liquid type seal.

It will be understood that applicant has shown a number of modifications to illustrate different means by which his improved sealing ring structure may be utilized to effectively provide a reliable seal for a peripheral opening in a centrifugal device. It is understood that all ring structures provide stabilizing supports to maintain the sealing ring in concentric relation and to hold it against uneven and undesired movements in radial or axial directions with respect to the axis of rotation of the centrifugal devices which fall within the scope of the appended claims and are contemplated as portions of the invention.

What is claimed is:

1. A centrifugal sealing ring structure comprising an annular metal ring adapted to be supported adjacent to and inwardly from an annular outlet, means connected to said ring for rigidly supporting the same in a fixed position with respect to the outlet, and a resilient expandable member carried by said ring, said expandable member being substantially co-extensive with the annular outlet and constructed and arranged to move radially outwardly from the

rigid ring in response to centrifugal force during rotation of the sealing ring thereby engaging and sealing the outlet.

2. A centrifugal sealing ring structure adapted to be positioned adjacent to and inwardly from an annular outlet formed by the opposed faces of a pair of rotatable members comprising an annular sheet metal support, said metal support having an annular peripheral edge portion adapted to be connected between the opposed faces of the rotatable members whereby the sheet metal support is fixedly held with respect to the annular outlet, and an annular resilient expandable member carried by said sheet metal support in spaced and co-extensive relation from the annular outlet, said expandable member being constructed and arranged to move radially outwardly from the annular sheet metal support in response to centrifugal force during rotation of the ring structure thereby engaging and sealing the annular outlet.

3. A centrifugal sealing ring structure adapted to be positioned adjacent to and inwardly from an annular outlet formed by the opposed faces of a pair of rotatable members comprising an annular sheet metal support, said support projecting into the annular opening and being adapted to be connected between the opposed faces of the members whereby the sheet metal support is fixedly held with respect to the annular outlet, and an annular resilient expandable member carried by the sheet metal support in spaced and coextensive relation from the annular outlet, said expandable member being arranged and constructed to move radially outwardly from the annular sheet metal support in response to centrifugal force during rotation of the sealing ring structure thereby engaging and sealing the annular outlet.

4. A device as set forth in claim 3 in which the annular sheet metal support includes an annular corrugated peripheral edge adapted to be positioned between the opposed faces of the rotatable members.

5. A device as set forth in claim 3 in which the annular sheet metal support is a flat annular ring having spacing buttons on opposite sides of the ring, the spacing buttons being adapted to be positioned between the opposed faces of the rotatable members.

6. A device as set forth in claim 3 in which the annular sheet metal support includes a ring having a plurality of spacing elements extending radially outwardly and being adapted for connection between the opposed faces of the rotatable members.
